United States Patent Office.

WILLIAM SMITH, OF PINE HILL, WISCONSIN.

Letters Patent No. 91,049, dated June 8, 1869.

STUMP-EXTRACTOR.

The Schedule referred to in these Letters Patent and making part of the same.

To all whom it may concern:

Be it known that I, WILLIAM SMITH, of Pine Hill, in the county of Jackson, and State of Wisconsin, have invented a new and improved Stump-Extractor; and I do hereby declare that the following is a full, clear, and exact description thereof, which will enable others skilled in the art to make and use the same, reference being had to the accompanying drawings, forming part of this specification.

Figure 1 is a sectional elevation of my invention, the section being taken through the line $x-x$ of fig. 2.

Figure 2 is a front view of the same.

Similar letters of reference indicate corresponding parts.

The object of this invention is to furnish a stump-extracting machine, which is simple in construction and effective in operation.

It consists, in general terms, of a gallows-frame, provided at its upper part with a ratchet-wheel and pawl-lever, the shaft of the ratchet-wheel bearing a gear-pinion, which engages with another gear-wheel on the winding-shaft or drum. The stump-chain being attached to this latter shaft or drum, is wound thereon when the ratchet-lever is vibrated, and great purchase is by this means obtained.

The gallows-frame is attached to the axle of a cart, in such a manner that it can be tipped up in a vertical position near a stump, and again drawn forward in a horizontal position upon the axle, when it is to be transported to another stump.

The machine will be more clearly understood by reference to the drawings, in which the gallows-frame is shown, composed of the two uprights, C C, arising from the foot-timbers H H, and braced by the timbers D, and cross-timbers G E.

A are the wheels, and B, the axle of the cart, and I, the tongue. The cart may be constructed in any suitable manner, and the gallows-frame may be also differently constructed, if desired, but I have shown what I deem to be the simplest and best method of constructing the same.

The axle and gallows-frame are connected by two pairs of linked eye-bolts i i, and so arranged in the braces D, that the wheels I will be slightly raised from

the ground when the gallows-frame is in an upright position for operation. This arrangement is to allow for the settling of the foot-timbers H in the ground, from the strain which is sustained in extracting the stump.

b is a shaft, bearing a ratchet-wheel, g.

The same shaft also bears a pinion, l, which engages with the cog-wheel J, mounted on the winding-shaft a, to which latter the stump-chain is attached.

f is a socket or box, working on the shaft b, and contains a hook-pawl, which engages the teeth of the ratchet-wheel g, when the lever is vibrated downwards.

h is a pawl arranged to hold the ratchet from turning backward while the lever is being raised. The bearings for the shafts a and b are afforded by the gallows-frame in any suitable manner.

The outline of the machine, in blue color, in fig. 1, illustrates the position of the gallows-frame and wheels when the machine is being backed up to a stump, or is being drawn forward to another place.

I desire it to be understood as not limiting my invention to the precise arrangement of shafts and gearing, or to the number of such shafts and gear-wheels, as it may be found expedient in practice to interpose one or more additional wheels between the two herein shown, in order to obtain greater purchase for extracting very large stumps. The number shown, however, is, if properly proportioned, sufficient to enable a single attendant to extract the stumps ordinarily found in practice.

Having thus described my invention,

I claim as new, and desire to secure by Letters Patent—

The arrangement upon the stump-extractor frame, attached to the wagon-wheels, of the winding-shaft a, wheel J, pinion l, ratchet-wheel g, and pawl h, the lever and the hook-pawl f e, as herein set forth and shown, for the purpose specified.

WILLIAM SMITH.
